UNITED STATES PATENT OFFICE.

PAUL O. WITTE, OF MINNEAPOLIS, MINNESOTA.

VEHICLE-TOP.

1,335,085.

Specification of Letters Patent. Patented Mar. 30, 1920.

Application filed July 17, 1919. Serial No. 311,411.

To all whom it may concern:

Be it known that I, PAUL O. WITTE, a citizen of the United States, residing at Minneapolis, in the county of Hennepin and State of Minnesota, have invented certain new and useful Improvements in Vehicle-Tops, of which the following is a specification.

The invention relates to folding vehicle tops which are adapted to be manipulated by one person both when folding and unfolding the top.

The invention provides a top particularly designed for automobiles and which when extended is firmly braced in every direction and capable of withstanding the strain incident to shock and vibration and which when folded will occupy a relatively small space and obviate projecting parts which would tend to present an unsightly appearance.

The drawing illustrates a preferred embodiment of the invention. However, it is to be understood that in adapting the same to meet different conditions, various changes in the form, proportion, and minor details of construction may be resorted to without departing from the nature of the invention as claimed hereinafter.

Referring to the accompanying drawing,

Figure 1 is a side view of a vehicle top embodying the invention showing the same extended, the dotted lines indicating the cover; and

Fig. 2 is a perspective view of the frame comprising the top showing the same in folded position.

Corresponding and like parts are referred to in the following description and indicated in both views of the drawing.

The top comprises a cover which is indicated by dotted lines in Fig. 1 and a supporting frame, the latter comprising a back bow 1, an intermediate bow 2, a folding front bow comprising sections 3 and 4, extensible side braces embodying members 5 and 6 and a stretcher bow 7 which is pivotally connected to the forward members of the extensible side braces.

The bows 1 and 2 are of ordinary construction and are pivoted at their lower ends to the body 8 of the vehicle at 9. Studs 10 and 11 project forwardly from the side members of the intermediate bow 2. The studs 10 are somewhat longer than the studs 11 to admit of the side extensible braces

coming between the sections 3 and 4 of the front view when the supporting frame is folded, as shown most clearly in Fig. 2.

The front bow is adapted to occupy a horizontal position when the top is extended, as indicated most clearly in Fig. 1 and its sections 4 are pivotally connected to the studs 11. The side members of the front bow are pivotally connected at 12 and the pivoted ends are upwardly deflected, as shown most clearly in Fig. 1, whereby provision is had for the extensible side braces to come between the sections 3 and 4 when the top is folded, as indicated in Fig. 2.

The extensible side braces may be of any construction and are pivotally connected to the studs 10 at their rear ends and are similarly connected at their forward ends to studs 13 projecting upwardly from the rear ends of the section 3. The members 5 and 6 may be slidingly connected in any way and in the event of the section 6 being tubular, the sections 5 may telescope therewith. These extensible braces materially assist in stiffening and strengthening the supporting frame of the top and provide for the two-fold movement of the section 3 when folding or unfolding the top. It should be remembered that the section 3 pivots with reference to the section 4 and at the same time swings with the section 4 toward and away from the intermediate bow 2, whereby the forward portion of the top may fold into compact form, as indicated in Fig. 2.

The stretcher bow 7 constitutes a tie for connecting the extensible side braces and preventing spreading or inward displacement of the sections 3 and 4 intermediate of their ends. The stretcher bow 7 also forms a support for the cover which rests thereon, as indicated in Fig. 1. The stretcher bow 7 is pivotally connected to the forward members 5 of the extensible side braces. Studs 14 provided on the members 5 have the ends of the bow 7 pivoted thereto. Stops 15 on the members 5 support the stretcher bow 7 in operative position, as indicated in Fig. 1.

The cover is indicated by the dotted lines 16 in Fig. 1 and is attached at its rear end to the rear of the body 8 and extends over the supporting frame and is adapted to be attached thereto in any manner. When the top is extended it is held in operative position by means of straps 17 in a manner well understood. When it is required to

fold the top the straps 17 are disconnected at their lower ends from the body 8 and the front bow is folded upon itself and against the intermediate bow 2, after which the 5 several bows are folded upon the body so as to occupy a position substantially as indicated in Fig. 2.

The foregoing description and the drawing have reference to what may be considered the preferred, or approved form of 10 my invention. It is to be understood that I may make such changes in construction and arrangement and combination of parts, materials, dimensions, et cetera, as may 15 prove expedient and fall within the scope of the appended claims.

Having thus fully described my invention, what I claim as new and desire to secure by Letters Patent is:—

20 1. A folding vehicle top, comprising a supporting frame work embodying front, intermediate and back bows, the intermediate and back bows being pivoted at their lower ends to each other and to the body 25 of the vehicle and the front bow being adapted to occupy a horizontal position when the top is extended, and having pivotal connection with the intermediate bow and comprising front and rear sections 30 which are pivotally connected, studs extending upwardly from the front section of the front bow, other studs extending horizontally from the upper part of the intermediate bow, telescoping sides, braces 35 disposed above the front bow and having

their members pivoted to the respective studs, a stretcher bow pivotally connected at its ends to the forward members of the side braces and stops on the forward members of the braces normally supporting the 40 stretcher bow in operative position.

2. A folding vehicle top, comprising a supporting frame embodying front, intermediate and back bows, the intermediate and back bow being pivotally connected to each other and to the body of the vehicle 45 and the front bow being adapted to occupy a horizontal position when the top is extended and pivotally connected to the intermediate bow and comprising sections 50 which are pivotally connected, the pivotal ends being upwardly deflected, extensible side braces disposed above the front bow and extending over the joint thereof and pivotally connected to the intermediate bow 55 and the forward section of the front bow, a stretcher bow pivotally connected to the front members of the extensible side braces and stops on said front members to support the stretcher bow in operative position, the 60 stretcher bow and the extensible side braces being adapted to occupy a position between the sections of the front bow when the latter is folded.

In testimony whereof I affix my signature 65 in presence of two witnesses.

PAUL O. WITTE.
